F. Y. MCKENNEY

SOAP AND WATER GUN

Filed Jan. 14, 1925

UNITED STATES PATENT OFFICE.

FRED Y. MCKENNEY, OF CHATTANOOGA, TENNESSEE, ASSIGNOR TO THE KELLY MANUFACTURING COMPANY, OF CHATTANOOGA, TENNESSEE, A CORPORATION OF TENNESSEE.

SOAP AND WATER GUN.

Application filed January 14, 1925. Serial No. 2,378.

- My invention relates to a soap and water gun intended to be used on the end of a hose line or faucet or mounted on a handle in any convenient way for washing railway 5 cars, buildings, floors and the like. It is an object of my invention to provide a device of the character described which may be adjusted to provide a soapy solution or clear water as desired.
- 10 A further object of the invention is to provide a device of this character with means for applying pressure of steam or compressed air to the water of the soapy solution if desired.
- 15 Referring to the accompanying drawing which is made a part hereof and on which similar reference characters indicate similar parts,
- Figure 1 is a perspective of my device in 20 position on a brush, and
- Figure 2, a side elevation on a larger scale with parts broken away to show the interior construction.
- 25 In the drawings reference character 10 indicates the cylindrical outer casing of the device which has removable heads at 11 and 12 and a perforated container 13 for soluble material. The perforated container is star-shaped in section with corrugations running from end to end, and tapers from one end to the other, the larger end being open or provided with a cover of wire gauze or the like to retain the soap or other soluble material in the container while the lower or left-hand end is closed except for an opening to receive the pipe 14.
- 30 The pipe 14 is supported on the head 12 preferably in a position extending approximately axially of the casing 10. As here shown the head 12 has flanges 15 and 16 concentric with a threaded flange surrounding the end of the casing. A plate 17 fits inside the flange 15 and against a shoulder thereof, said plate 17 having a rearwardly extending externally-threaded portion engaging threads on the flange 16. The plate 17 has 35 passages for liquid preferably formed as nipples 18 extending toward the container 13.
- 40 The head 12 has an axial passage 19 for liquid and is adapted to be connected to a faucet or the like by a union 20. A three-way valve 21 intersects the passage and is adapted to establish communication with a lateral passage 22. When the valve is in 55 the position shown water or other liquid will pass directly through the pipe 14 and a part will also flow into the passage 22 and thence to a chamber 23 communicating with the nipples 18.
- 60 The head 11 terminates in a threaded reduced portion supporting a nozzle 24 in line with the opening of the pipe 14. A nozzle 25 is supported axially of nozzle 24 and is adapted to apply the pressure of steam or 65 compressed air to the outgoing liquid. The nozzle 25 communicates with a pipe 26 for this purpose and the flow of gas is controlled by a cock 27.
- 70 Figure 1 illustrates one manner in which the device may be utilized. As here shown the casing 10 has straps 28 applied thereto adjacent the heads which straps terminate in hooks 29 extending over the handle 30 of a brush 31. A pipe 32 is attached to the 75 device by a union 20 and a pipe 33 is secured to the nozzle 24. This enables the user to apply clear rinsing water to the floor or other work being cleaned by the brush 31 by turning the valve 21 into a position opposite that shown whereby the branch passage 34 of the valve extends downward and is shut off. He may also apply a mixture of soap and water with the valve in the position illustrated in Figure 80 2 or a mixture containing a larger proportion of soap by turning the valve so as to bring its branch 34 into horizontal position extending toward the right and its branch 35 into vertical position, the branch 36 then 85 extending vertically downward whereby all the entering fluid must pass through the nipples 18 so as to impinge on the soap in the container.
- 90 It will be understood that granular soap 95 may be used in the container whereupon the water will be sprayed on the soap and will flow over and through the grains and out through the perforations 37. Solid or semi-liquid soap may also be used, the only limitation being that the soap shall not be soft enough to run out through the perforations 37. Semi-liquid soap being most easily handled is preferred for use in my device and it will be seen that in use the water will fall 100 in a spray on the surface of the soap and will run off immediately as a soapy solution without any chance of forming a liquid.
- 105

blanket over the body of soap by reason of the number of perforations 37. This tends to produce a very uniform solution at all stages of use regardless of whether there be much or little soap in the container. Such free flow is facilitated by the tapering form of the container and also by the star-shaped conformation whereby the outer edges of the container may bear against the casing at the upper end or against supporting devices in the casing while the remainder of the surface remains free to permit the solution to flow freely out through the walls of the container and down along the same.

15 The terms water and soap are used for convenience in the specification but it will be understood that any soluble material may be used in the container and any suitable solvent can be used in connection therewith.

20 It will be obvious to those skilled in the art that various changes may be made in the device without departing from the spirit of the invention and therefore I do not limit myself to what is shown in the drawing and 25 described in the specification but only as indicated in the appended claims.

Having thus fully described my said invention, what I claim as new and desire to secure by Letters Patent, is:

30 1. In a solution apparatus, a cylindrical casing, a perforated longitudinally corrugated container for soluble material fitting in the casing at one end and tapering toward the other, an inlet for a solvent at one end 35 of the casing, and an outlet at the other end, substantially as set forth.

2. In a solution apparatus, a cylindrical casing, a perforated longitudinally corrugated container for soluble material fitting 40 in the casing at one end and tapering toward the other, an inlet for a solvent at one end of the casing, an outlet at the other end, and means arranged axially of the casing for injecting gas under pressure into the 45 solution at said outlet, substantially as set forth.

3. In a solution apparatus, a cylindrical casing, a perforated longitudinally corrugated container for soluble material fitting 50 in the casing at one end and tapering toward the other, an inlet for a solvent at one end of the casing, an outlet at the other end, a nozzle concentric with said outlet said nozzle pointing outward, and a pipe for supplying 55 gas under pressure leading to said nozzle, substantially as set forth.

4. In a solution apparatus, a casing, a

soap container in the casing having a perforated longitudinally corrugated outer wall tapering from the inlet end of the casing 60 toward the outlet end, and means at the inlet end for spraying water into the container the perforations in the container being so proportioned to the inlet means that the solution runs off as fast as formed to 65 prevent blanketing of the soap, substantially as set forth.

5. A mixing device comprising an outer casing, a perforated container for soluble material within the outer casing and comprising a wall having a greater surface area than a container of a shape corresponding to that of the outer casing, removable heads for each end of said casing, a perforated spray plate supported by one of said heads 70 said last mentioned head having a plurality of concentric flanges one of which engages said outer casing and the other of said flanges supporting said plate, a tube disposed longitudinally in the casing and connecting said head with the casing beyond said perforated container and means for directing a solvent through said head against said plate or through said head and said tube into the container, substantially as set 75 forth.

6. A mixing device comprising an outer casing, a perforated container for soluble material within the outer casing and comprising a wall having a greater surface area 80 than a container of a shape corresponding to that of the outer casing, removable heads for each end of said casing, a perforated spray plate supported by one of said heads said last mentioned head having a plurality 85 of concentric flanges one of which engages said outer casing and the other of said flanges supporting said plate in spaced relation inwardly of said head, forming with the head a chamber in the end of the casing, a tube disposed longitudinally in the casing, and connecting said head with the casing beyond 90 said perforated container, and means for directing a solvent alternately through the head and tube into the casing or through the head and chamber into the container or 95 through both at once, substantially as set forth.

In witness whereof, I have hereunto set my hand at Chattanooga, Tennessee this 8th day of January, A. D. nineteen hundred and twenty-five.

FRED Y. McKENNEY.
